UNITED STATES PATENT OFFICE.

FREDERICK B. REILLY, OF BRONX, NEW YORK.

DESIGN FOR A FLASK.

Application filed December 18, 1928. Serial No. 29,328. Term of patent 3½ years.

To all whom it may concern:

Be it known that I, FREDERICK B. REILLY, a citizen of the United States, residing at Bronx, county of Bronx, and State of New York, have invented a certain new, original, and ornamental Design for a Flask, of which the following is a specification, reference being had to the accompanying drawing, forming part thereof.

The figure is a front view of a flask constituting my new design.

I claim:

The ornamental design for a flask, as shown.

FREDERICK B. REILLY.
